UNITED STATES PATENT OFFICE.

FRANCIS E. TYNG, OF IRVINGTON, NEW YORK.

TIME-RECODER.

SPECIFICATION forming part of Letters Patent No. 448,560, dated March 17, 1891.

Application filed May 8, 1890. Serial No. 350,995. (No model.)

To all whom it may concern:

Be it known that I, FRANCIS E. TYNG, of Irvington, in the county of Westchester and State of New York, have invented a new and 5 Improved Time-Recoorder, of which the following is a full, clear, and exact description.

My invention relates to improvements in time-recorders; and the object of my invention is to produce a recorder which will easily 10 and accurately record the hours of labor of a large number of people.

To this end my invention consists in certain features of construction and combinations of parts, which will be hereinafter fully described, 15 and pointed out in the claims.

Reference is to be had to the accompanying drawings, forming a part of this specification, in which similar letters of reference indicate corresponding parts in all the figures.

20 Figure 1 is a side elevation of the device, the inclosing case and dial-plate being shown in vertical longitudinal section. Fig. 2 is a broken detail plan view of the time-card used in connection with the device. Fig. 3 is a 25 vertical transverse section on line $x-x$ of Fig. 1, with parts broken away and in section. Fig. 4 is a broken detail view of the cylinder, showing the means of attaching the time-card thereto. Fig. 5 is a plan view of the dial- 30 plate, and Fig. 6 is a detail view of the mechanism for indenting the time-card.

A suitable inclosing case A, which is preferably rectangular in form, is provided with a base A' and a removable cover A², said cover 35 comprising approximately a quarter-section of the case. A frame B is mounted in the case A, said frame comprising a base-plate B' and two vertical end portions B², said portions being provided with the upwardly-extending 40 arms B³, as shown in Fig. 3. A horizontal shaft C is mounted centrally in the frame B, the two ends being supported by the center pieces a and a², which project through the end portions B² of the frame just below the 45 junction of the arms B³. The center pieces are provided with a screw-thread, in the usual manner, with conical points, and with suitable check-nuts a' and a², by which their position may be regulated.

50 A cylinder D is fixed to one end of the shaft C, and fixed to the shaft at one end of the cylinder is a bevel-pinion d, which meshes

with the gear-wheel e on the lower end of the vertical shaft E, said shaft projecting upwardly through the sleeve F' of the dial-plate 55 F, which is mounted on the upper portion of the case, and the shaft being supported by the bracket E', which is fixed to the upper portion of the case and extends downwardly into the case, the shaft E being provided with 60 a suitable collar E², which prevents any vertical movement of the shaft.

The dial-plate F is fixed to the top of the case A, is provided with the depending sleeve F', which extends through the top of the case, 65 and has inscribed on its upper face a series of numbers, which, as shown, run from 1 to 31, but which may be increased to any desired extent, the numbers on the dial-plate corresponding with the numbers on the time- 70 card, as hereinafter described.

An annular plate or disk G rests loosely in a corresponding recess of the dial-plate F, said plate being fixed to the upper end of the vertical shaft E and having attached thereto 75 an upwardly-extending handle G', so that by turning the handle the plate and shaft will be revolved and the motion will be transmitted by means of the gear-wheel e and pinion d to the shaft C and cylinder D. The plate 80 G is also provided with a pointer f, which extends across a portion of the plate and may be made to indicate any particular number on the dial-plate F.

At the end of the cylinder D opposite the 85 pinion d is a ratchet-wheel H, which is fixed to the end of the shaft C, and the teeth of which are engaged by a pawl g, so as to permit the wheel and shaft to be turned in one direction only. The pawl g is pivoted in the 90 upper end of a vertical support g', arranged adjacent to the ratchet-wheel H and fixed upon the base-plate B' of the frame B, said pawl being held in position against the ratchet-wheel by the spring g², which is fixed 95 to the support g' and which presses against the back of the pawl.

A time-card I is wrapped around and attached to the cylinder D, said time-card having at one end a series of spaces h, in which 100 the names of the various employés are inscribed, a series of spaces h' to contain the numbers of the employés, a series of time-spaces h², occupying the central portion of the

- card, each of said spaces representing fifteen minutes of time and having opposite thereto and upon one edge of the card the hours and half hours of a day, being numbered in the illustration from 6 to 6, and a series of spaces h^3 , in which the total number of hours' work is inscribed. It is obvious that the card may be divided into time-spaces representing longer or shorter periods of time.
- 10 The time-card I is attached to the cylinder D as follows: In the face of the cylinder D are two parallel longitudinal grooves i , in which fit closely the parallel rods i' , said rods being provided with suitable knobs or buttons i^2 to facilitate their easy removal from the grooves i and having at one end beveled projections i^3 , which fit in the perforations j' of the spring-plates j , said plates being fixed to each end of the cylinder D, so as to extend 20 to the outer edge of the same. The time-card I is wrapped around the cylinder, the edges of the card are inserted in the grooves i , the rods i' are placed in the grooves, thus binding the time-card therein, and the rods 25 are pressed downwardly until their beveled ends i^3 are engaged by the perforations j' of the spring-plates j , thus securely holding the rods and card in position. To remove the card, the spring-plates j are pressed outwardly 30 and the rods i' removed.
- 15 Mounted in the ends of the arms B³ of the frame B are the horizontal shafts J and J', which extend the entire length of the frame and the ends of which are mounted on suitable center pieces k, which project through the end portions of the frame and have conical points, as shown, and suitable check-nuts k', by which their position may be regulated. The shaft J is provided with a threaded portion J², which is opposite the cylinder D, and 40 which is somewhat longer than the cylinder, and the shaft J' is smooth throughout its length.
- 20 Mounted on the shafts J and J' so as to extend across from shaft to shaft above the cylinder D is a bridge or frame K, having at each end suitable sleeves K', adapted to move upon the shafts J and J', and having near each end the upwardly-projecting standards 25 L and L', said standards being in horizontal alignment. The frame K has centrally mounted therein, so as to extend vertically through a perforation in the same, a bolt m, having at its lower end a point to engage the 30 time-card on the cylinder D, and having its upper end suitably headed, as shown, said bolt being held normally from engagement with the time-card by the spring m', which encircles the upper portion of the bolt, the 35 upper end of the spring pressing against the bolt-head and the lower end resting upon the frame K. A support l is fixed to the frame K adjacent to the bolt m and in horizontal alignment therewith, said bolt being adapted 40 to limit the downward movement of the arm M, which is pivoted in the standard L and extends inwardly and partially across the

bridge, having its free end beveled, as shown, and having attached to the lower side thereof a spring M², which is attached at its lower end 70 to an eye on the frame K and which holds the arm upon the support l.

A lever M' is centrally pivoted in the support L' and its inner end is held normally below the end of the arm M by the spring M³, 75 the upper end of which is fixed to the lever and the lower end of which is fixed to the frame K. The lever M' has pivoted to its inner end a finger-piece M⁴, having a beveled shank, as indicated by the dotted lines in 80 Fig. 6, and which is normally held in alignment with the lever M' by the spring M⁵, which is fixed to the top of the lever and which presses upon the top of the finger-piece M⁴. It will thus be seen that said finger-piece may swing upwardly, but the beveled shank will prevent it from swinging below a horizontal position, so that when the outer end of the lever is depressed the finger-piece will engage the inner end of the arm M 90 and raise the arm, and when the inner end of the lever M' has passed above the arm M the finger-piece M⁴ will swing upwardly when the lever is again depressed by the spring M³ and permit the inner end of the lever to pass below the inner end of the arm.

Pivoted upon one edge of the bridge K is a bent arm n, said arm being centrally pivoted upon the bridge and extending above the threaded portion J² of the shaft J, the end 100 of the arm above said threaded portion being provided with a tooth n' to engage the thread of the shaft, and the inner end of the arm is engaged by a spring n², which is fixed to the bridge K in such a manner as to press 105 upwardly against the arm, and so hold the tooth n' in engagement with the thread of the shaft J, so that when the shaft is turned the frame K, being connected thereto, as 110 shown, will be moved longitudinally upon the shafts J and J'.

A clock-movement N is mounted upon suitable supports N' in the rear of the case A, said movement being provided with a gear-wheel p, which meshes with the pinion o on 115 the shaft J, so that the motion of the clock-gear will be transmitted to the shaft and turn the same. The clock-work is provided with suitable winding-stems q, and any of the ordinary clock-movements may be used.

A bar P is arranged above the outer end of the lever M', said bar being vertically movable on the supports P', which are fixed to the cover A² and project downwardly into the case A, and the bar P is held normally from 125 engagement with the lever M' by the springs r, which encircle the supports P' and are attached at their lower ends to the bar P and at their upper ends to the upper portion of the supports P', so as to hold the bar in an 130 elevated position.

A rod R is hinged to a plate t on the cover A² of the case and extends transversely across the upper portion of the case and is bent

downwardly and has a horizontal portion R', which rests upon the bar P. A spindle S, having at the top a suitable knob S', is mounted vertically in a sleeve S² in the cover 5 A², and the lower end of said spindle rests upon the rod R, so that when the spindle is depressed the rod R and bar P will be depressed and the lever M' actuated.

In using this device the thread on the shaft 10 J and the gear mechanism connecting the said shaft with the clock-movement should be so adjusted that the frame K will be moved a distance on the shafts J and J' corresponding to the time-spaces on the time-card I, and 15 the gear mechanism connecting the shaft E with the shaft C should be so adjusted that when the pointer on the plate G at the upper end of the shaft E is opposite a certain number on the dial-plate F the bolt m will be 20 above a space representing a similar number on the time-card. As shown in the accompanying drawings, the time-card is adapted for a single day's use; but it is obvious that 25 the cards may be adapted for a longer or a shorter period. It will be seen that by means of the handle G' the cylinder D may be turned without interfering with the shafts J and J' or the clock-movement.

To set the device the inner end of the arm 30 n is depressed, thus releasing the tooth n' from engagement with the shaft J, and the frame K is moved to the extreme right of the cylinder, as shown in Fig. 1.

It will be seen that when the frame K is 35 placed opposite the hour at which the day's work begins it will be moved by the clock-movement, so that the bolt m will be continually opposite a space representing the hour of the day, and that by marking upon the time- 40 card the hour when a person begins work and the hour when he leaves off the actual working time will be accurately recorded.

To illustrate, we will suppose that John Doe begins work at seven o'clock a. m., as 45 indicated by the time-card in Fig. 2. The cylinder is turned to bring his No. 1 in line with the bolt m in the bridge. The spindle S is then depressed, thereby actuating the rod R and bar P, as described, thus depressing 50 the outer end of the lever M' and raising the inner end. As the inner end of the lever is raised the finger-piece M¹ will engage the inner end of the arm M and raise the arm until the piece M¹ passes above the same, when the 55 spring M² quickly forces the arm downward, and the arm striking the bolt m will depress the bolt and perforate the time-card opposite the hour 7, as shown in Fig. 2. If Doe stops work at five o'clock, as shown on the time- 60 card, the spindle S is again depressed, thus actuating the mechanism, as described above, and making another indentation opposite the hour five p. m. and opposite the name John Doe, thus indicating that the number of hours' 65 work is ten, which number is placed in the space h³ opposite the name of Doe.

It will be seen that in using this invention

each employé has a particular number and the number on the time-card and on the dial-plate correspond, and if, when an employé 70 begins and leaves off his work, the machine is operated as described the exact number of hours' work must be recorded. Before striking the spindle S and operating the device the cylinder D is turned by means of the 75 handle G', so as to bring the number of the employé opposite the bolt m.

Having thus described my invention, I 80 claim as new and desire to secure by Letters Patent—

1. A time-recorder consisting, essentially, of a cylinder mounted upon a suitable shaft and having a time-card thereon, as shown, a dial-plate connected by a gear mechanism with the cylinder, the numbers on the plate 85 corresponding to the numbers on the cylinder, a frame mounted upon suitable shafts above the cylinder and having means connected therewith for marking the time-card, and a clock-movement connected with said 90 frame so that the frame will be moved thereby, substantially as described.

2. A time-recorder consisting, essentially, of a revoluble cylinder mounted in a suitable frame and having a time-card thereon containing a series of names, a series of hour-spaces, and a series of numbers corresponding to the names, a dial-plate having numbers thereon corresponding to the numbers of the time-card, a disk mounted in the dial- 95 plate, provided with a suitable pointer and connected by a gear mechanism with the cylinder, a frame mounted upon shafts, so as to move longitudinally above the cylinder, said frame having means for marking the time- 100 card, as shown; and a clock-movement connected with the frame, so that the frame may be moved thereby, substantially as described.

3. A time-recorder consisting, essentially, of a revoluble cylinder having a time-card 110 thereon containing a series of spaces for the names of the employés, a series of spaces for the numbers of the employés, and a series of hour-spaces, a dial-plate having numbers inscribed thereon corresponding to the numbers 115 of the time-card, a disk having a pointer fixed thereto adapted to rotate in a recess of the dial-plate and connected by a gear mechanism with the cylinder, a frame mounted upon shafts above the cylinder, one of said 120 shafts being threaded, as shown, means for indenting the time-card from said frame, means for connecting the frame with the threaded portion of the shaft, and a clock-movement geared to said threaded shaft and 125 adapted to move the shaft and frame, substantially as described.

4. A time-recorder consisting of a revoluble cylinder having a time-card thereon containing a series of name-spaces, a series of time- 130 spaces, and a series of number-spaces, as shown, a dial-plate having numbers thereon corresponding to the numbers of the time-card, a disk adapted to rotate in a recess of

the dial-plate, having an indicating-pointer thereon and connected by a gear mechanism with the cylinder, a pawl-and-ratchet mechanism for preventing the backward movement of the cylinder, a frame mounted upon shafts above the cylinder, one of said shafts being threaded, as shown, means for marking the time-card from said frame, a detachable connection between the frame and the threaded shaft, and a clock-movement geared to the threaded shaft and adapted to move the shaft and frame, substantially as described.

5. In a time-recorder, the combination, with the cylinder D, having grooves i therein, and the time-card I, of the rods i' , having the projecting ends i^3 , as shown, and the spring-plates j , fixed to the cylinder ends and having perforations to receive the ends of the shafts, substantially as described.

10. 6. The combination, with the revoluble cylinder D, having the time-card I attached thereto, and the frame K, mounted above the cylinder and having means, as shown, for operating the same, the said frame having arranged thereon the standards L and L', and the central support l of the spring-actuated bolt m , projecting through a central perforation, of the frame K, the spring-actuated arm M, pivoted in the standard L and extending above the support l and bolt m , the lever M', having the finger-piece M ^{4} mounted therein and having a spring, as M ^{3} , attached thereto, and means, as spring-actuated bar P, rod R, and spindle S, for actuating the lever M', arm M, and bolt m , substantially as described.

15. 7. In a time-recorder having a revoluble cylinder carrying a time-card, the combination, with the parallel shafts J and J', the shaft J being threaded, as shown, and operated by a clock-movement, of the frame K, mounted loosely upon said shafts and carry-

ing means for indenting the time-card, as described, and the bent arm n , pivoted to the frame K, provided with a tooth n' to engage the thread of the shaft J, and a suitable spring for holding said tooth and threaded shaft in engagement, substantially as described.

8. In a time-recorder, the combination, with the shaft C and cylinder D, fixed thereto, said cylinder carrying a time-card, substantially as described, of the dial-plate F, having numbers inscribed thereon corresponding to the numbers of the time-card, the plate G, provided with a suitable handle and a pointer f to indicate the numbers of the dial, a gear mechanism connecting said plate to the shaft C, the ratchet-wheel H and spring-actuated pawl g for preventing the backward movement of the shaft C, the shafts J and J', mounted in the frame B above the cylinder, the shaft J being screw-threaded and geared to a clock-movement, as shown, the frame K, mounted upon said shafts and connected by the bent arm n with the threaded portion of the shaft J, the spring-actuated bolt m , mounted in the frame K and adapted to indent the time-card on the cylinder, the spring-actuated arm M, adapted to engage said bolt, said arm being pivoted to a suitable support, as shown, the spring-actuated lever M', pivoted in a suitable support and having a movable finger-piece M ^{4} to engage the end of the arm M and elevate the same, and means, as spring-actuated bar P, rod R, and spindle S, for tilting the lever M', substantially as described.
